G. W. CONLEY

SMOKING PIPE

Filed March 23, 1921

Inventor

G.W. Conley
By Watson E. Coleman
Attorney

UNITED STATES PATENT OFFICE.

GEORGE W. CONLEY, OF WHEATON, ILLINOIS.

SMOKING PIPE.

Application filed March 23, 1921. Serial No. 454,668.

To all whom it may concern:

Be it known that I, GEORGE W. CONLEY, a citizen of the United States, residing at Wheaton, in the county of Du Page and State 5 of Illinois, have invented certain new and useful Improvements in Smoking Pipes, of which the following is a specification, reference being had to the accompanying drawings.

10 This invention relates to certain improvements in smoking pipes, and it is an object of the invention to provide a pipe with novel and improved means whereby the pipe is prevented from clogging and whereby a dry 15 and cool smoke is assured.

It is also an object of the invention to provide a smoking pipe with novel and improved means whereby saliva is prevented from passing through the stem of the pipe 20 into the mouth of the user.

Furthermore, it is an object of the invention to provide a smoking pipe having novel and improved means whereby the lower portion of the chamber of the bowl of the pipe 25 is maintained dry so that the formation of a wet heel is eliminated and thus enabling the smoker to get as fresh a smoke at the last as when he first lit the tobacco charge.

The invention consists in the details of 30 construction and in the combination and arrangement of the several parts of my improved smoking pipe whereby certain important advantages are attained and the device rendered simpler, less expensive and 35 otherwise more convenient and advantageous for use, as will be hereinafter more fully set forth.

The novel features of my invention will 40 hereinafter be definitely claimed.

45 In order that my invention may be the better understood, I will now proceed to describe the same with reference to the accompanying drawings, wherein:

Figure 1 is a view partly in side elevation 50 and partly in section illustrating a smoking pipe constructed in accordance with an embodiment of my invention; and

Figure 2 is a view similar to Figure 1 illustrating a further embodiment of my 55 invention.

As disclosed in the accompanying drawings, B denotes the bowl of a smoking pipe provided with a stem 1. The outer portion α of the bore 2 of the stem is enlarged and in 60 the extremity of the enlarged portion α is adapted to be received an extremity of the

mouth-piece 3. Extending within the inner portion of the bore 4 of the mouth-piece 3 with a snug or tight fit is an elongated sleeve or supplemental stem 5, said stem being of 60 a length to extend within the smaller portion β of the bore 2 of the stem 1 when the mouth-piece 3 is in applied position.

The wall of the sleeve or supplemental stem 5 is provided with a plurality of longitudinally spaced openings 6 and the wall of said sleeve or stem, at a point substantially diametrically opposed to an end opening 6 and particularly the opening adjacent the mouth-piece 3, is provided with a relatively 70 large opening 7. The bore of the sleeve or supplemental stem 5, at a point inwardly of and immediately adjacent the diametrically opposed openings 6 and 7, is intersected by a plug or partition 8. The plug or partition 75 8 is insertible within the supplemental stem at either end of said stem.

As herein disclosed, the openings 6 are three in number and the second end opening 6 is particularly for the purpose of providing means whereby the adjacent end portion of the bore of the sleeve or supplemental stem 5 may be thoroughly cleansed when the requirements of practice so necessitate. The opening 7, hereinbefore referred to, is also 80 for the purpose of providing means whereby the opposite end portion of the bore of the sleeve or supplemental stem 5 may be properly cleansed.

In practice, smoke from the bowl is drawn 85 into the chamber afforded by the enlarged portion α of the bore 2 of the stem 1 through the sleeve or supplemental stem 5 and the intermediate opening 6. The smoke then is drawn from the chamber through the outer 90 opening 6 and also through the opening 7 and through the outer portion of the sleeve or stem 5 and into the mouth of the smoker through the mouth-piece 3. The periphery 95 of the supplemental stem 5 is substantially smooth and unobstructed throughout the length thereof so that the possibility of oil or the like from tobacco collected on the stem is substantially eliminated, and thereby minimizing the liability of the openings 6 and 7 becoming clogged.

In view of the foregoing it will be at once understood that the enlarged portion α of the bore 2 of the stem 1, when the pipe is completely assembled, serves as a chamber to collect saliva which may pass down through the bore of the mouth-piece 3 so that the form-

ing of a wet heel within the bowl is prevented, as the lower portion of the bowl is maintained dry, thus enabling the smoker to get as fresh a smoke at the last as when he first lit the charge within the bowl. The partition or plug 8 within the sleeve or supplemental stem 5 is preferably of wood and serves to stop the heat from within the bowl passing directly through the mouth-piece 3 so that a cool smoke is assured.

In addition to providing means for facilitating the cleansing of the sleeve or supplemental stem 5, the opening 7 provides means whereby saliva which may pass down through the bore of the mouth-piece 3 may be drained into the chamber afforded by the enlarged portion *a* of the bore 2 of the stem 1 and for which reason it is to be understood that in assembling my improved pipe, the large opening 7 is arranged at the bottom or below.

In the embodiment of the invention as illustrated in Figure 1, the sleeve or supplemental stem 5' is applied in the same manner as has been hereinbefore set forth with respect to the sleeve or supplemental stem 5. However, the upper wall of the supplemental stem or sleeve 5' is provided with only two longitudinally spaced openings 6' with the forward or outer opening 6' having substantially diametrically opposed thereto a drain opening 7' for saliva. The sleeve or stem 5' has its bore at a point between the openings 6' intersected by the partition or plug 8'.

Each of the sleeves or supplemental stems 5 and 5' is provided in one end portion with the notches 9. These notches 9 serve as an indicating medium so that the user may assemble the complete pipe with convenience and facility. The notches 9 indicate to the

user the end portion of the supplemental sleeve or stem 5 or 5' which is to be arranged within the mouth-piece.

From the foregoing description it is 45 thought to be obvious that a smoking pipe constructed in accordance with my invention is particularly well adapted for use by reason of the convenience and facility with which it may be assembled and operated, and 50 it will also be obvious that my invention is susceptible of some change and modification without departing from the principles and spirit thereof and for this reason I do not wish to be understood as limiting myself to 55 the precise arrangement and formation of the several parts herein shown in carrying out my invention in practice except as hereinafter claimed.

I claim:

A smoking pipe including a bowl and a stem, the outer portion of the bore of the stem being enlarged, a removable mouth-piece insertible within the outer end of the stem, a sleeve extending through the enlarged portion of the bore of the stem and having its opposite end portions engageable within the inner portion of the bore of the stem and the inserted end portion of the bore of the mouth-piece, the periphery of said 70 sleeve being smooth and unobstructed and a partition intersecting the bore of the sleeve, the wall of said sleeve being provided with openings at opposite sides of the partition, said openings communicating with the enlarged portion of the bore of the stem, said partition being insertible within the sleeve through either end thereof.

In testimony whereof I hereunto affix my signature.

GEORGE W. CONLEY.
